(57) **CLAIM**

The ornamental design for a milling bit, as shown and described.

DESCRIPTION

FIG. 1 is a perspective view of a milling bit, according to a new design;

FIG. 2 is a front elevation view thereof;

FIG. 3 is a side elevation thereof;

FIG. 4 is a rear elevation thereof;

FIG. 5 is a top plan view thereof; and,

FIG. 6 is a bottom plan view thereof.

The broken lines shown in the drawings show portions of the milling bit which form no part of the claimed design.
